(57) **CLAIM**

The ornamental design for a fitting hinge, as shown and described.

DESCRIPTION

FIG. 1 is a perspective view of a fitting hinge embodying our new design, wherein elements shown in broken lines form no part of the claimed design;

FIG. 2 is a perspective view seen from rear side thereof;

FIG. 3 is a front view thereof;

FIG. 4 is a rear view thereof;

FIG. 5 is a top plan view thereof;

FIG. 6 is a bottom view thereof;

FIG. 7 is a left side view thereof;

FIG. 8 is a right side view thereof;

FIG. 9 is a front view in close state thereof;

FIG. 10 is a rear view in close state thereof;

FIG. 11 is a perspective view seen from front side in a closed state thereof; and,

FIG. 12 is a perspective view seen from rear side in a closed state thereof.
